UNITED STATES PATENT OFFICE.

JAMES E. LAPPEN, OF LE ROY, MINNESOTA, ASSIGNOR, BY MESNE ASSIGNMENTS, TO NORTHERN INSULATING COMPANY, OF ST. PAUL, MINNESOTA, A CORPORATION OF MINNESOTA.

PROCESS OF PRODUCING FLAX FELT.

1,125,347.

Specification of Letters Patent.

Patented Jan. 19, 1915.

No Drawing.

Application filed August 13, 1908. Serial No. 330,274.

To all whom it may concern:

Be it known that I, JAMES E. LAPPEN, a citizen of the United States, residing at Le Roy, in the county of Mower and State of Minnesota, have invented certain new and useful Improvements in Processes of Producing Flax Felt; and I do hereby declare the following to be a full, clear, and exact description of the invention, such as will 5 enable others skilled in the art to which it appertains to make and use the same.

This invention has for its object to produce from flax straw or felt self sustaining sheets of long-fiber tow felt, suitable for 10 heat insulating purposes; or, in other words, of the kind disclosed and claimed in my Patent, 908,681, of January 5th, 1909; and the present invention consists in the novel 15 method or process for producing such flax 20 felt, and which novel process is hereinafter set forth and defined in the claim.

As is well known by all persons familiar 25 with this art, the stem of the flax plant is composed of an inner tube of wood, or 30 woody tissue, commonly called shive, the long or bast fiber directly outward of the wood or shive and an outermost skin, ordinarily called the cortical tissue. It is also 35 well known that this body of bast fiber is composed of bundles of filaments and these filaments, in turn are composed of the ultimate fibers which are hollow. The shive, or woody tissue, is also composed of ultimate fibers which are hollow, but the ultimate 40 fibers of the shive are relatively short as compared with the ultimate fibers of the bast. The bast fibers are many times longer than the shive. It is also well known that the bast and the cortical tissue contain 45 gummy materials which, when exposed to moisture and heat, will cause the mass of material containing the same to ferment. It is equally well known that caged or non-circulating dead air is a good non-conductor 50 of heat. It is not as good as a vacuum, but, if the air is confined in small cells so that circulation and convection cannot take place, it is perhaps the next best heat insulator to any commercially available vacuum.

55 The flax felt disclosed and claimed in my said Patent, 908,681, utilizes the above stated principles to perhaps the greatest possible advantage; or, otherwise and briefly stated, it is a self sustaining material composed of the long, hollow fibers of the bast, and the

comparatively short fibers of the shive from which sufficient of the gum has been removed to prevent the fermentation thereof and which are afterward felted together into a sheet and then compressed and dried, thereby rendering available the hollow fibers of the bast and the shive for the encagement of air therein, and also encaging great quantities of air in the spaces or interstices between the felted fibers. This product is produced preferably from flax tow, but coarse grades thereof can be produced directly from the flax straw, as the same comes from an ordinary threshing machine. It is better, however, to first run the threshed straw 60 through an ordinary tow machine so as to knock off more or less of the shive and thereby get what is commercially known as upholstering tow, or a product which is a little more than half bast fiber and a little less 65 than half shive. When in this condition, the shive in the tow will be in broken and splintered form, chiefly adherent to the bast; but there will be some shive entirely detached from the bast, but held tangled up 70 therewith to a greater or less extent, and there will be some of the bast which is entirely free from shive.

Whether the flax straw, itself, or the flax tow be used as the starting point, 75 the process of treatment to get the above noted product, is as follows: The flax straw or tow is first cooked in a suitable digester, containing an alkaline or equivalent chemical solution of the proper strength, 80 for the proper length of time to soften up the fibrous elements and to remove the fermentable gums therefrom, or so much thereof as is necessary for the purpose intended. Then the cooked material is submerged in water and manipulated therein to get the fibrous elements uniformly 85 distributed and into interlacing or felted relations in respect to each other while they are held in suspension in the 90 water. The cooked material, as it comes from the digester, is in bunches or lumpy tangled masses of various sizes utterly incapable, without further treatment, of being 95 felted together into a sheet of uniform 100 thickness and texture. It has been customary to grind up such cooked stock by treating the same in a beating engine until the stock was brought into the form of pulp 105 and then to use this pulp in the customary 110

way for the manufacture of paper, but such a product is unsuitable for heat insulating purposes. I discovered that, by the proper treatment of the said bunches or masses 5 of long-fiber stock cooked in a chemical solution, as above stated, the said bunches or masses could be torn apart and their fibrous elements separated and that, by properly manipulating the same in water, 10 said fibrous elements could be re-arranged and re-distributed into a uniform mass with the elements thereof held in suspension in the water in interlacing or felting position. Hence, the second and most important step 15 of the process is the manipulation of said cooked stock in water to get the said fibrous elements so distributed into interlacing or felting relations to each other while they remain suspended in the water, as above 20 stated. The preliminary cooking in the chemical solution is, however, highly important for getting the said stock into such condition that its said fibrous elements can be so re-arranged and brought into felting 25 relation by the proper manipulation thereof, while suspended in water. Without the said chemical treatment, the gums or pecto- 30 material in the bast would hold the bundles of filaments cemented together and they would not open up or come apart when suspended in water. Moreover, said gums must be removed—or most thereof—to prevent the presence of fermentable material in the final product. The raw, or uncooked 35 shive, is of such a hard and stubborn nature that it will not lend itself to interlacing or felting purposes, until it is first softened up by such cooking. Shive, in its said raw or natural state, is, when dry, of less specific 40 gravity than water and will float on the top of the same. The bast fiber, whether raw or cooked will stand in suspension in the water. The shive, after it has been cooked, 45 as above described, will also stand in suspension in the water. Hence, whether the shive remains adherent to the bast, as most of it does, or is loose therefrom, as some of it will be, as the cooked stock comes into the water and after it has been properly 50 manipulated therein, the whole thereof will remain submerged or, in other words, all the fibrous elements will stand in suspension in the water; and, hence, by the proper careful manipulation of these fibrous elements 55 so suspended in the water, they can be brought into the uniform distribution required with the elements standing in the interlacing or felting relations, as above set forth.

60 From the foregoing, it will be seen that the successful manipulation of the stock in the water is very dependent upon the preliminary cooking thereof in the proper chemical solution for the proper length of 65 time. It must, of course, be obvious that

unless the said uniform re-arrangement and re-distribution of the said fibrous elements can be made while the said elements remain suspended in the water to get the same into interlacing or felting relations in respect to 70 each other, no product of uniform texture or even approximately uniform texture could be produced. After the said fibrous elements have been brought to the desired uniform distribution and remain suspended in 75 the water in interlacing or felting relation, the next step of the process is to remove this uniformly distributed mass of fibrous elements from the water in such a way as to complete the felting action. This can be 80 done by any suitable gathering device raised through the water from below the suspended mass of fibrous elements and which gathering device is adapted to catch and hold on its face the felting fibrous elements 85 while permitting the water to escape through the felting fibrous mass. An ordinary screen of the proper mesh may be used for the purpose when done by hand, or an under running apron, properly constructed, and which emerges from the water, 90 may be used if so desired. The downward flowage of the water through the felting fibrous mass on the face of the screen, or other gathering device, carries more or less 95 of the finer fibers into intertwining relations with the coarser fibers and with each other, thereby further perfecting the felting action as the screen or gathering device emerges from the water. The hand manipulation 100 of the fibrous elements suspended in the water continues while the gathering device is being lifted through the water but no longer and there is no shaking of the gathering device after it emerges from, or 105 while it is within the water.

The final step of the process is to compress and dry the felted material into a self sustaining sheet, and this may be done in any suitable way.

110 The finished sheet can be of any desired thickness, according to the amount of the cooked stock which, after being properly manipulated in water to get the fibrous elements properly suspended therein, as above 115 described, is removed at one time or on any given section of the gathering device as it emerges from the water. It is the custom and practice to make the sheets from half an inch to an inch and one-half in thickness, varying according to the usage intended.

120 After the felted material has been properly compressed, and thoroughly dried, it is, of course, obvious that all the tubular ultimate fibers of the bast and of the shive, and that all the interstices between the felted fibrous elements, will contain dead air engaged therein; or, in other words, air held 125 therein in such a way that no circulation 130

thereof can take place sufficient to afford any material convection of heat.

The finished sheet is not only self sustaining, but is flexible, yielding and tough 5 because of its long-fiber texture; which qualities well adapt this flax felt to be readily applied to the great diversity of structures wherein heat insulation is desired. It is especially well adapted for use 10 as a lining for refrigerators, cold storage compartments, house sheathing, roof and floor under-linings and, generally, wherever a good heat insulator is needed. It has gone into the most extensive use on refrigerator 15 cars. Inasmuch as the fermentable gums were removed by the cooking and the chemical solution, this flax felt will stand moisture and heat without fermentation. However, for the best heat insulation, it must be kept 20 dry. It is also worthy of note that it is a slow burner; it will burn, but does not readily do so.

The above described process for producing the above identified long-fiber flax felt may, 25 of course, be carried out with the aid of any suitable apparatus; and this is thought to be so obvious that illustration of such apparatus is not needed. Digesters, suitable for use in effecting the cooking of the 30 flax straw or tow in a suitable chemical solution, are old and well known in this art. The only additional essentials, for carrying out the process by hand, is a suitable vat containing water in which the cooked stock 35 can be manipulated to get the fibrous elements uniformly distributed in interlacing or felting relation, while held suspended therein, and a suitable gathering device, such as a screen or its equivalent, for removing 40 said suspended stock thereby from the water to complete the felting action; and suitable compressing and drying means to compact and dry the felted material into the finished sheet.

45 Although, up to the present time, I have never been able to carry out the second step of the process, above set forth, to-wit, the re-distribution and re-arrangement of the cooked stock in water, required to get the 50 fibrous elements uniformly distributed and suspended therein in proper felting relations, without more or less hand manipulation, I have been able to greatly reduce the amount of hand manipulation required 55 by the use of suitable mechanism, such as that disclosed in my prior Patent 1,023,473, of date, April 16, 1912, entitled "Flax felt

machine". The mechanism disclosed in that machine will tear apart the chunks or masses of cooked stock and separate the same up into 60 smaller portions in the water, but some further hand manipulation is required to get the fibrous elements uniformly distributed and suspended in the water in interlacing or felting relation above the removing apron 65 or gathering device of that machine. That machine also discloses suitable mechanism for compressing and drying the felted material into a felted sheet.

It should, perhaps, be noted that the 70 water in the felting vat should be kept changing, or have a fresh water inlet and a suitable outflow, especially if reliance is to be placed upon the manipulation in the water in said vat to wash out the chemical 75 liquor from the cooked stock. If desired, however, the cooked stock may be washed after it is dumped out from the digester to remove the liquor therefrom before the cooked material is put in the felting vat, 80 and, in that event, the changing of the water in the felting vat need not be so frequently made.

What I claim is:

The process of producing from flax straw 85 or tow self sustaining sheets of long-fiber flax felt, suitable for heat insulating purposes, which process consists in first, cooking the flax straw or tow in an alkaline or equivalent chemical solution to soften the 90 fibers and remove fermentable gums therefrom; secondly, in manipulating all of said cooked stock in water to get the fibrous elements uniformly distributed into interlacing or felting relations in respect to each 95 other, while held in suspension in the water; thirdly, in the removal of this suspended uniform mass of fibrous elements from the water by a suitable gathering device adapted to catch and hold on its face 100 the felting fibrous elements while permitting the water to escape through the felting fibrous mass, thereby completing the felting action as the gathering device emerges from the water; and, finally, in compressing and 105 drying the felted material into a self sustaining sheet, substantially as described.

In testimony whereof I affix my signature in presence of two witnesses.

JAMES E. LAPPE.
